[57] CLAIM

The ornamental design for controller for label printing and applying machine, as shown and described.

DESCRIPTION

FIG. 1 is a front elevational view of a controller for label printing and applying machine showing our new design;

FIG. 2 is a left side elevational view thereof;

FIG. 3 is a top plan view thereof;

FIG. 4 is a right side elevational view thereof;

FIG. 5 is a rear elevational view thereof;

FIG. 6 is a perspective view thereof;

FIG. 7 is a bottom plan view thereof.

FIG. 3

FIG. 2

FIG. 1

FIG. 7

FIG. 4

FIG. 5

FIG. 6
